CONTROLLING APPARATUS FOR AUTOMOBILE-RADIATOR SHUTTERS.

1,289,969.

Specification of Letters Patent.

Patented Dec. 31, 1918.

Application filed March 9, 1918. Serial No. 221,388.

To all whom it may concern:

Be it known that I, EDGAR TREGONING, a citizen of the United States, residing at Attleboro, in the county of Bristol, State of Massachusetts, have invented certain new and useful Improvements in Controlling Apparatus for Automobile-Radiator Shutters, of which the following is a specification.

My invention relates to apparatus for controlling the temperature of internal-combustion engines and consists particularly of an improved mechanism for automatically operating a shutter or other closure to regulate the passage of the air through the radiator of the water-cooling system.

The object of my invention is to provide a thermostatically-controlled electrically-operated device for opening and closing the shutter or other air-shield of the radiator under the influence of changes in temperature in the engine or motor. A particular object of the improvement is to adapt the device to be operated with a low voltage current, and to automatically switch off the current after the shutter has been opened or closed to prevent depleting the supply of electricity or exhausting the battery. Further objects of the improvement are to render the device positive in action, while being extremely sensitive of control, and to simplify its mechanism and insure it against derangement or getting out of order.

The manner and means for carrying out these improvements are fully described in the following specification, illustrated by the accompanying drawings, in which like reference characters designate like parts. In the drawings:—

Figure 1 is a general view showing an automobile engine with its water-cooling radiator, the air-shield or shutter therefor, and the manner of applying my improved device thereto;

Fig. 2, an enlarged, detail view of a section of the air-shield or shutter, showing it closed;

Fig. 3, a similar view showing the shutter-slats opened;

Fig. 4, a diagrammatic view or chart of the electrical wiring-connections for the device;

Fig. 5, an enlarged, front elevation of the operating-mechanism of the device;

Fig. 6, a side view of the same; and

Fig. 7, a detail view of one of the circuit-breaking switches of the apparatus.

Referring first to Fig. 1, C designates the upright cylinders of a motor or internal-combustion engine of conventional type, A the chassis of the automobile on which it is mounted, and R the radiator disposed in front of the motor and communicating with the water-jackets of the cylinders through suitable connections as usually arranged, but not herein shown or described. The casing or shell of the radiator R is extended at the front in an overhanging rim or frame F on which is mounted the shutter S or other closure for obstructing the passage of the air through the radiator. Any suitable arrangement of air-shield may be employed for this purpose, and as here shown it comprises the shutter S having series of vertical slats s provided with trunnions p pivoted in openings in the flanges f of the radiator-frame F. As illustrated in the detail views, Figs. 2 and 3, the lower trunnions or hinge-pins p of the slats s are bent around to provide right-angled arms or elbow-pieces e having extensions d which are pivotally-connected at i to a horizontally-extending link or connecting-rod I. This provides for coupling all of the several shutter-slats s to swing in unison and they may be operated through any suitable means such as the crank-arm P rigidly connected to one of the pintles or trunnions p.

The operating-mechanism for the shutter S is preferably located at the rear of the radiator R within the space inclosed by the hood or bonnet of the motor. For supporting the apparatus, I employ a vertical standard or upright G which may be fastened to the engine base and steadied at the top by a strut or brace g bolted to the forward cylinder. The parts of the operating-mechanism are mounted on the standard or support G and protected by a removable cover or casing H fitted thereto. As before stated, the operation of the device is controlled from a thermostat T, which may be of any preferred type, mounted on one of the engine cylinders C as illustrated in Fig. 1.

Referring now particularly to Figs. 5 and 6, the controlling-mechanism for opening and closing the shutter S comprises essentially a vertically-slidable rod K connected to a bell-crank lever O which, in turn, is connected with the shutter crank-arm P by a wire link N. The control-rod K slides in angle-shaped brackets 2, 3 fastened to the front of the standard G, and is provided at

its lower end with a right-angled extension *k* engaging a slot 4 in one of the arms of the bell-crank *O*. The bell-crank *O* is pivoted on a bearing *o* projecting from the standard 5 *G*, and into its lower arm is hooked the end of the link *N* which couples it to the crank-arm *P* on the shutter-hinge *p*. The rod *K* is adapted to be slid upwardly in its bearings through the influence of a pair of solenoids *M*, *M'* acting on a slidable armature *U* which is of U-shape and secured to the rod at *u*. The downward movement of the rod *K* is controlled by gravity and for this purpose the weight of the armature *U*, which 10 is preferably of laminated structure and relatively heavy, assists in its operation. As illustrated in Figs. 5 and 6 the rod *K* is in raised position with the slats of the shutter *S* opened, as shown in Fig. 3, so that 15 20 when the rod slides downwardly the bell-crank *O* will be rocked to turn the crank-arm *P* to close the shutter as illustrated in Fig. 2. Above the bearing 3 is a coil-spring 5 surrounding the rod *K* to adapt it to act 25 as a buffer to relieve the shock as the armature *U* falls against it.

The solenoids *M*, *M'* are mounted on angle-shaped brackets 6 and 7 secured to the front of the standard *G*, and the upper 30 bracket 6 is extended and bent around at 8 to adapt it to support a pair of magnet-coils *W*, *W'*. Fastened to the top of the bracket 6 is a fork-like bearing-member 9 formed with upstanding ears 10 in which 35 is pivoted a horizontal rod or pin 11. Fastened to the center of the pin 11 is an arm or lever 12, preferably constructed of sheet-metal with its end bent around the pin and clamped thereto by means of a screw 13. 40 Suitable bushings 14 are arranged between the sides of the lever 12 and the ears 10 to hold the pin 11 in place in its bearings. The lever 12 carries a cross-bar 15 arranged opposite the ends of the cores 16 of the coils 45 *W*, *W'* to serve as a movable armature therefor. At the rear of the armature 15 is an arm 17 reaching out from the standard *G* and carrying a screw 18 at its end which 50 serves as an adjustable stop for the armature 15 to regulate its throw away from the magnets. The armature 15 is normally held away from the magnet-cores 16 by a spring 19 acting on the arm or lever 12. One end of the spring 19 is anchored to an eye 20 on 55 the standard *G* while its opposite extremity is hooked through the end of an adjustable stud or screw 21 threaded through an offset arm 22 on the lever 12. The screw 21 may be adjusted longitudinally to regulate the 60 tension of the spring 19, and is held from unwarranted turning by suitable check-nuts 23.

At the upper end of the lever 12 is a block 65 24 formed with a detent-shoulder 25 adapted to engage with the edge 26 of a detent-

block or catch 27. The rod *K* extends through a hole in the block 27 and the latter is secured in place thereon by means of a set-screw 28, and is formed with an inclined face 29 adapted to coact with an oppositely-beveled face 30 on the block 24. That is to say, as the rod *K* is raised in its bearings the beveled face 29 on the block 27 will ride across the incline 30 on the block 24 to tilt the lever 12 outwardly and thereby 70 allow the detent-shoulders 25, 26 to come into engagement to hold the rod *K* suspended as shown in Fig. 6. The lever 12 is rocked or tilted outwardly to release the detents 24 and 27, to allow the rod to drop, through 75 the influence of the magnets *W*, *W'* acting on the armature 15 in the manner as more fully explained hereinafter.

The upward movement of the detent-block 27 also serves a further purpose, that of 80 throwing open a switch *L* which controls the flow of current through the solenoids *M*, *M'*. The switch *L*, shown in detail in Fig. 7, is carried at the upper end of the arm 12 extending laterally thereof. It may be of any 85 suitable construction and as here shown comprises a fixed blade 35 secured to the arm 12, with an insulating washer 36 interposed therebetween, and a spring-blade 37 held in opposite, spaced relation therewith. The 90 spring-blade 37 is fastened at one end to an insulating-block 38 which, in turn, is secured to the end of the fixed blade 35, the screws 39, 40 which hold the blades in place 95 extending only part way through the block 100 38. The screws 39, 40 also serve as binding-posts for the wires which connect the switch *L* in circuit with the solenoids *M*, *M'* and the source of current, these connections being described in detail hereinafter. At the outer 105 ends of the two blades 35, 37 are suitable studs 41, 42 which serve as contacts to close the circuit through the switch when the spring-blade 37 is allowed to swing toward the fixed one 35. The contact points 41, 42 110 are normally held apart to interrupt the circuit, as shown in Fig. 7, by means of a pin or stud 43 which bears against the detent-block 27. One end of the pin 43 is fastened to the spring-blade 37 by a screw 44, while 115 its opposite end extends loosely through an opening 45 in the blade 35 and arm 12 to adapt it to be engaged by the block 27.

Mounted on the upper end of the standard *G* is a second switch *J* which is operated 120 automatically by the movement of the rod *K* to open and close the circuit through the magnets *W*, *W'*. As shown in Figs. 5 and 6 the switch *J* comprises two opposite spring-blades 46 and 47 secured to clips 48, 49 which 125 are fastened to the standard *G* by screws 50, 51. The blades 46, 47 are bent inwardly at their upper, free ends but are prevented from contracting by a strip of insulating-material 52 secured to one of them. On the 130

upper end of the rod K is a collar 54 of insulating-material clamped thereto by a screw 55. The collar 54 carries a pin 56 projecting toward the standard G to adapt it to slide in between the ends of the spring-blades 46, 47 to close the circuit therethrough.

On one side of the standard G is a forwardly-projecting plate V, see Fig. 5, constructed of vulcanized rubber or other insulating-material, and adapted to serve as a mounting for three binding-posts *x*, *y* and *z* to which the current wires are connected. Each post comprises a screw 60 extending through the plate V with washers 61, 62 on either side and suitable binding-nuts 63, 64 for tightening the wires in place. Connected to the upper binding-post *x* is a wire 65 leading to the movable-blade 37 of the switch L with its end secured thereto by the screw 39. From the screw 40 of the opposite fixed-blade 35 a wire 66 leads to one of the solenoids M which is connected at its opposite terminal with the other coil M' by a cross-wire 67. From the opposite terminal of the coil M' a wire 68 leads to the lower binding-post *z*. The post *z* is also connected to one of the magnet-coils W, W' by a wire 69, and the two coils W, W' are connected in circuit by a cross-wire 70. From the terminal of the coil W a wire 71 leads to one of the blades 46 of the upper switch J, being connected thereto by the screw 50. Connected to the other blade 47 of the switch J by the screw 51 is a wire 72 leading to the middle binding-post *y*. Referring now to Fig. 4, which shows the wiring connections in diagram, a wire 73 leads from the lower binding-post *z* to one pole of a battery represented at B, or, if preferred, the current might be supplied by a generator at this point. Leading from the opposite pole of the battery B is a wire 74, grounded at 75 in the metal-frame or chassis A of the machine, see also Fig. 1.

As before stated, the thermostat for controlling the apparatus may be of any suitable arrangement and I have preferred to herein illustrate it as comprising a cylindrical casing T mounted on a tubular stem *t* which is inserted in a suitable opening *c* drilled through the water-jacket of one of the engine cylinders C. Referring to Fig. 4, a spring-coil 76 is contained within the stem *t* of the thermostat with one of its ends connected to operate an arm 77 pivoted to turn on the axis of the casing T. The arm 77 is adapted to be swung to the right or left under the action of the contraction or expansion of the spring-coil 76 as influenced by cold or heat. On opposite sides of the swinging arm 77 are two spring-arms 78, 79 attached at their lower ends to binding-posts 80, 81 secured in the casing T, but insulated therefrom. The arms 78, 79 carry

contacts 82, 83 at their upper ends with which a contact-member 84 on the movable arm 77 engages as the latter swings to one side or the other. In Fig. 4 the arm 77 is shown in contact with the right-hand 70 spring-arm 79 and it will be noted that the arms are adapted to yield to prevent restricting the action of the spring 76 which would be liable to injure its delicate structure. The arm 77 acts as the circuit-controlling element for the electrical apparatus of the shutter-operating mechanism, and is grounded at 85 in the engine cylinder whereby to complete the circuit to the battery through its ground 75. The binding-post 80 of the left-hand contact-arm 78 is connected by a wire 86 with the upper binding-post *x* on the standard G, and, as before explained, the post *x* is connected through the switch L with the solenoids M, 85 M'. From the other binding-post 81 of the right-hand contact-arm 79 a wire 87 leads to the middle binding-post *y*, which latter is connected in circuit with the magnets W, W' through the upper switch J. Having 90 now described the construction and arrangement of the parts of my improved device, its method of operation will next be explained:

Normally, in warm weather, the rod K, 95 which acts as the prime-mover for operating the shutter S, is held in raised position, as shown in Fig. 6, with its catch 27 engaged by the shoulder 25 on the detent-block 24. With the parts in this relation 100 the lower arm of the bell-crank O will be rocked to the right, see Fig. 5, to hold the shutter-slats *s* in open relation, as shown in Fig. 3, to permit a free circulation of the air through the radiator R illustrated in 105 Fig. 1. Now, when the weather becomes cold so that the cooling system of the engine causes its temperature to drop below what is required for maximum efficiency of operation the thermostat T will be influenced to 110 control the apparatus in the following-described manner to close the shutter S to prevent further circulation of air through the radiator. As before explained, the contraction of the spring-coil 76 in the thermostat T, under the effect of a relatively 115 low temperature, will cause its arm 77 to swing to the right, as viewed in Fig. 4, to make contact with the arm 79. This action of the arm 77 closes the electrical circuit leading from the binding-post 81 through the wires 87, 72 to the switch J; thence through the wire 71 to the magnets W, W'; and through the wires 69, 68, 73 to the battery B; the circuit being completed from the battery through the grounds 75 and 85 back to the arm 77. With the rod K in raised position, as shown in Figs. 5 and 6, the switch J will be closed by the pin 56 120 on the collar 54 contacting with both switch- 125 130

blades 46, 47. The current from the battery B will therefore flow through these above-described connections to energize the magnets W, W' and consequently the armature 15 will be attracted by their cores 16. The movement of the armature 15 causes the lever 12 to be rocked to the right, as viewed in Fig. 6, and the detent-block 24 will thereby be slid out from under the catch or detent 27. This release of the detents allows the rod K to drop under the influence of gravity acting on its weight or armature U, and through its connection with the bell-crank O the latter will be rocked to act through its link N and the crank-arm P to swing the slats s on their hinges to close the shutter S as shown in Fig. 2. As the rod K slides downwardly through its bearings the armature U brings up against the buffer-spring 5 to relieve the shock, and meanwhile the contact-pin 56 carried at its upper end is withdrawn from between the blades 46, 47 of the switch J. This latter action breaks the circuit at the switch J so that the current is immediately shut off and magnets W, W' will be deenergized without further drain on the battery. As the armature 15 is released the spring 19 will swing the lever 12 back to its original position as regulated by the adjustable stop-screw 18.

The parts of the apparatus will remain in the above-described relation with the shutter S closed until the temperature of the engine becomes abnormally high, and it is to be noted that during this period of inoperation of the device the current is entirely shut off at the switch J. On the other hand, the switch L will have been allowed to close, due to the withdrawal of the detent-block 27 from the end of the pin 43 as the rod descended. That is to say, immediately the rod K drops, the detent 27 slides from under the end of the pin 43 on the blade 37 to permit the latter to spring toward the fixed blade 35 to close the contact at 41, 42, see Fig. 7. Referring to Fig. 4, the switch L controls the circuit for the solenoids M, M' comprising the wires 73, 68 leading from the battery B to the coil M'; the wire 66 leading from the coil M to the fixed switch-blade 35; and the wires 65, 86 leading from the movable blade 37 to the binding-post 80 of the left-hand contact-arm 78 in the thermostat T. As long as the temperature of the engine is not raised above a certain point, as regulated by the adjustment of the thermostat through suitable means usually provided, but not herein shown or described, the electrical circuit just described will remain open. That is to say, the arm 77 will fluctuate in position between the two contacts 82, 84 without engaging either of them, but should the temperature of the engine become

excessively high, then the expansion of the coil 76 will swing the arm 77 to the left to cause it to make contact with the end of the arm 78. Immediately this contact occurs, the circuit to the battery B is closed through the grounds 85 and 75. The switch L being also closed, as above explained, the current will flow through the circuit to energize the solenoids M, M' and the latter will act on the core-member or armature U to draw it upwardly within the coils. The raising of the armature U slides the rod K upwardly in its bearings and the bell-crank O is thereby rocked back to its original position shown in Fig. 5 to open the shutter-slats s, as illustrated in Fig. 3. As the rod K moves upwardly the inclined side 29 of the detent 27 rides against the beveled face 30 of the block 24, see Fig. 6, to force the lever 12 outwardly against the action of its spring 19, and finally the shoulder 25 on the block 24 engages the edge of the catch 27 to hold the rod suspended. Meanwhile, as the detents come into locking engagement the side of the block 27 will act against the end of the pin 43 on the movable switch-blade 37, see Fig. 7, to force the contact-plug 42 away from the plug 41 to break the circuit. It will thus be seen that as the rod K reaches the end of its upward throw and is locked in place the circuit through the solenoids M, M' is immediately broken at the switch L to shut off the current from the battery. At the same time the pin 56 at the upper end of the rod K is carried into engagement with the blades 46, 47 to close the switch J to prepare the device for further operation when the opposite circuit is completed at the thermostat T as first explained.

It will be observed that my improved apparatus is extremely simple in construction and arrangement, and while adapted for very sensitive control is entirely positive in action. That is to say, the opening and closing of the radiator-shutter is effected positively by the action of the rod K, which is shifted in one direction by gravity and in the other through the attraction of the solenoids on the armature U. The delicately-constructed thermostat is employed only for closing the electrical circuit to energize the magnet- and solenoid-coils and therefore is relieved of all strain or stress which might tend to overcome its sensitiveness. It is also to be noted that the electrical mechanism of the apparatus can be operated from a current of low voltage and with the use of the current for only a brief period at each operation. In other words, the device is entirely automatic and self-controlling so that the current is switched off immediately the shutter-operating means has acted in either direction. This provides against wasting the current and exhausting the battery and

therefore makes for more positive action, while insuring more efficient functioning of the device over long periods of time. The apparatus may be easily applied to practically all types of motor cars, and is also

5 adaptable for other purposes, such as the controlling of dampers for furnaces or boilers. When once installed it requires no further attention and its freedom from complication renders it practically proof against derangement or getting out of order.

10 Various modifications might be made in the structure and arrangement of the parts of the device, or in the manner of applying it to use, without departing from the spirit or scope of the present invention; therefore, without limiting myself to the exact embodiment herein shown and described, what I claim is:—

15 20 1. In an apparatus for operating shutters on automobile radiators, the combination with a vertically-slidable control-member positively connected with the shutter to open and close the latter, of electrical means for raising said member, a latch carried by said member, a detent for engaging the latch to lock the member in raised position against the action of gravity, an electro-magnet for releasing the detent, a source of current in open circuit with said magnet, a thermostat for closing said circuit, and means to open the circuit upon the shifting of the control-member to prevent wasting the current.

25 30 35 40 45 50 2. In an apparatus for operating shutters on automobile radiators, the combination with a vertically-slidable control-member adapted to be shifted in alternately-opposite directions and positively connected with the shutter to open and close the latter, of electro-magnetic means for raising said member, a source of current in open circuit with said electro-magnetic means, a latch carried by the control-member, a movable detent for engaging the latch to hold the control-member in raised position at the end of its movement, an electro-magnet also in open circuit with the source of current, means operated by the energizing of the magnet to move the detent to release the catch on the control-member, and a thermostat for closing one circuit or the other under the influence of changes in temperature.

3. In an apparatus for operating shutters on automobile radiators, the combination with a plurality of automobile shutter-slats, of a link connected to tilt the slats to open and close the shutter, a bell crank connected to move the link, a vertically-slidable control-member connected to rock the bell-crank, electro-magnetic means for raising said control-member against the action of gravity, a source of current in normally-open circuit with said electro-magnetic means, a latch on the control-member, detent-means for engaging the latch on the

control-member to lock the latter in raised position at the end of its movement, an electro-magnet also in open circuit with the source of current, means operated by the energizing of the magnet to release the detent, and a thermostat for closing one circuit or the other under influence of changes in temperature.

4. In an apparatus of the type described, the combination with a vertically-slidable control-member, of electrically-operated means for raising said member, a latch carried by said member, a detent for engaging said latch to hold the member against downward movement under the action of gravity, an electro-magnet for releasing the detent, a source of current in normally-open circuit with the magnet, means for closing said circuit to energize the magnet, a switch in the circuit, and means operated by the control-member to close the switch when the detent is engaged with the latch and to open it upon the release of the detent.

5. In an apparatus of the type described, the combination with a vertically-slidable control-member, of electrically-operated means for raising said member, a catch on said member, a detent for engaging said catch, an electro-magnet, an armature operated by the magnet to release the detent from the latch, a source of current, a normally-open circuit connecting the source of current with the electrically-operated means, a second normally-open circuit connecting the source of current with the magnet, thermostatically-operated means for closing one circuit or the other under the influence of changes in temperature, a switch in the magnet-circuit, means operated after the release of the detent from the latch to open said switch, a switch in the solenoid circuit, and means operated by the engagement of the detent with the latch to open the last named switch.

6. In an apparatus of the type described, the combination with a vertically-slidable control-member, of electrically-operated means for raising said member, a latch on said member, a pivoted lever carrying a detent for engaging the latch to hold the control-member against downward movement under the action of gravity, an electro-magnet for rocking the lever to release the detent, a source of current in normally-open circuit with the magnet, means for closing said circuit to energize the magnet, a switch carried by the detent-lever, and means engageable with the latch on the control-member to open said switch when the detent is engaged with the latch and to close it upon the release of the detent.

7. In an apparatus of the type described, the combination with a vertically-slidable control-member, of an armature carried by said member, solenoids for attracting the ar-

- mature to raise the control-member, a source of current in open circuit with the solenoids, a latch on the control-member, a detent for engaging the latch to hold the control-member in raised position against the action of gravity, an electro-magnet for operating the detent to release it from the latch, an open circuit connecting the source of current with the magnet, automatically-operated means 5 for closing one circuit or the other, a switch in each circuit, and means carried by the control-member for opening one switch and closing the other after each shifting movement of the control-member.
10. 8. In an apparatus of the type described, the combination with a vertically-slidable control-member, of electrically-operated means for raising said member, a latch on said member, a detent for engaging said latch, an electro-magnet, an armature operated by the magnet to release the detent from the latch on the control-member, a source of current, a normally-open circuit connecting the source of current with the electrically-operated means, a second normally-open circuit connecting the source of current with the magnet, thermostatically-operated means for closing one circuit or the other under the influence of changes in temperature, a switch in each circuit, means carried by the control-member to open one switch when the latch is engaged by the detent, and means also carried by the control-member to close the switch in the other circuit when the latch is engaged by the detent. 20 25 30 35
- In testimony whereof I affix my signature.

EDGAR TREGONING.
